UNITED STATES PATENT OFFICE.

WILHELM ZOLPER, OF WILMINGTON, DELAWARE, ASSIGNOR OF ONE-HALF TO HARRY F. SCHNEPP, OF WILMINGTON, DELAWARE.

PUZZLE.

1,130,461.

Specification of Letters Patent. Patented Mar. 2, 1915.

Application filed November 3, 1914. Serial No. 870,029.

To all whom it may concern:

Be it known that I, WILHELM ZOLPER, a citizen of the United States, residing at Wilmington, in the county of New Castle, 5 State of Delaware, have invented a new and useful Puzzle, of which the following is a specification.

My invention consists of a game comprising a field, bases of different colors thereon disposed in cross form, pockets in said bases, a starting place, and spinning tops of different colors similar to those of the bases, so that by operating the tops and manipulating the field in the hand of the player, a top 10 may be pocketed on a base of the same color, and eventually producing a cross shaped figure of the tops, the goal of the game being the deposit of the tops in their places to complete said cross shaped figure in a number 15 of consecutive spins equal to that of the tops, in the present case, six in number.

It consists further of a devious course on the field which it is designed to have a spinner traverse so as to reach a goal which 20 will be of difficult nature, and so cause the exercise of much skill and patience to accomplish.

The invention is satisfactorily illustrated in the accompanying drawing, but the important instrumentalities thereof may be varied, and so it is to be understood that the invention is not limited to the specific details shown and described.

Figures 1 and 2 represent plan views of a 30 game embodying my invention, the spinners being in different places in the two figures. Fig. 3 is a section of a portion on the line x—x Fig. 2.

Similar numerals of reference indicate 40 corresponding parts in the figures.

Referring to the drawings:—1 designates the field of the game, the same being composed of a flat piece of card-board, paste-board or other suitable material and having 45 therein the series of openings forming the pockets 2 disposed in the order of a cross. Around the pockets of the cross are the bases 3 which in the present case are respectively, red, white and blue.

40 4 designates a series of spinning tops which are also respectively, red, white and

blue, and 5 and 6 designate what I denominate as starting places, the same in the present case being of the form of stars. Extending from the place 6 is the course line 7 55 which is formed on the field 1 and passes around certain of the bases 3, then between adjacent bases, and then entirely around one of the central bases, crossing at 8, and finally reaching the top base as at 9. 60

The operation is as follows:—The player holding the field in his hand takes one of the tops and starting at the place 5 spins it on the field and then manipulates said field, whereby the top is directed to one of the 65 bases of the same color as said top and guides it to the pocket thereof, so as to drop the bottom peg or point of the top into the latter. Then he proceeds with the other tops, when if he succeeds, he will eventually 70 pocket all of the tops on the bases of the same color, which is the goal of the game and counts so much for him, the failure to accomplish which counts against him. To render the game more difficult, the player 75 pockets all of the tops save the one at what may be called the upper base of the field which in this case is denominated as the goal. Then he starts at the place 6 spinning a top thereat and manipulates the field to cause the top to traverse the course 7 and follow the exact direction thereof, so as to reach said upper base into which he is to 80 pocket the top, which will be of the same color, it being found that in either case it 85 will require considerable skill or dexterity, patience, and a steady hand to accomplish the result, and so causing the game to be amusing and entertaining in its nature. 90

Having thus described my invention what I claim as new and desire to secure by Letters Patent, is:—

1. A game composed of a field, bases thereon, and pocket-openings in the field at said bases, said bases being of different colors, and spinning tops of different colors having their pegs adapted to be placed in the openings of bases of corresponding colors, said bases being disposed on the field of the form of a cross-shaped figure. 95

2. A game composed of a field, bases thereon, pockets in the field, said bases being 100

of different colors, spinning tops of different colors adapted to be placed in said pockets, and a devious course line on said field extending around the pockets from a 5 starting point to one of said pockets.

3. In a game composed of a field, bases on said field, and openings in said bases, a devious course on said field, the same extend-

ing from a starting place on the field and continuing on the latter around said bases 10 to one of the latter as a terminal and the goal of the game.

WILHELM ZOLPER.
